J. R. WINCHESTER.

Carriage-Top.

No. 11.144.

Patented June 20, 1854

UNITED STATES PATENT OFFICE.

JOSEPH R. WINCHESTER, OF MEDINA, NEW YORK.

MODE OF RAISING AND LETTING FALL CARRIAGE-TOPS.

Specification of Letters Patent No. 11,144, dated June 20, 1854.

To all whom it may concern:

Be it known that I, JOSEPH R. WINCHESTER, of Medina, in the county of Orleans and State of New York, have invented a new and Improved Mode of Raising and Letting Fall the Covers or Tops in Use upon Carriages of that Description Now in Ordinary Use; and I do hereby declare that the following is a description of the said 10 invention.

The nature of my invention consists in enabling the person riding in a carriage to which it is attached to raise the cover or top to the carriage or let it fall at pleasure 15 without inconvenience by means of a horizontal brace extending across from side to side of the carriage top just beneath the forward bow thereto and passing through said bow at the sides and attached to the 20 outside braces on either side and the desired effect is produced by making use of the cross brace as a lever operating at the same time upon the outside braces as will more fully appear by the drawing herewith sent. 25 And I further claim to have invented a material improvement in the outside braces, which improvement is in the part of the outside braces placed between and attached to the outside portions of said braces and 30 performs the office of a double brace, being immovable upon the bow to the top next the last or posterior one except as it turns upon the bolt by which it is fastened to said bow as will be seen by reference to 35 drawings.

Explanation of the drawing.—For a more full and complete idea of my invention reference is hereby made to the drawing here-with sent.

a a is a horizontal brace attached to the 40 outside braces *b b* at *c c*.

e e and *f f* are joints in the outside braces which are moved by pushing forward the horizontal brace *a a* when the carriage top is up and causing the top to fall back. The 45 meeting of the two parts of the outside braces at *g g* forms on either side a stiff joint made so by means of the bolt passing through the parts of braces and being then attached to the bow of the top next to the 50 one farthest back. Then from the above explanation it will be readily seen that the desired effect can easily be produced by said invention as set forth and claimed in my specification. 55

Then what I claim as my invention and desire to secure by Letters Patent is—

The cross brace attached to the outside braces and the center part of the outside braces performing as it does the office of a 60 double brace and the two attached to a carriage top or cover in connection with the other portions of the outside braces will produce the desired effect.

JOSEPH R. WINCHESTER.
